UNITED STATES PATENT OFFICE.

WILLIAM G. HAEHL, OF MANILLA, INDIANA.

WASHING-MACHINE ATTACHMENT.

Application filed May 31, 1927. Serial No. 195,485.

This invention relates to an attachment for washing machines of that type including an oscillatory rubber element, and the invention has for its object to provide, in a manner as 5 hereinafter set forth, means for detachably securing the rubber element stationary in a manner whereby the water dripping therefrom will be directed into a tub when the rubber element is shifted to a position to permit of the removal of the clothes from the tub, under such conditions overcome the objection of the water dripping upon the floor.

Further objects of the invention are to provide, in a manner as hereinafter set forth, an 15 attachment for the purpose referred to which is simple in its construction and arrangement, strong, durable, readily installed with respect to the tub and rubber element, thoroughly efficient and convenient in its use, and 20 inexpensive to manufacture.

With the foregoing and other objects in view the invention consists of the novel construction, combination and arrangement of parts, as hereinafter more specifically described, and illustrated in the accompanying drawings wherein is shown an embodiment of the invention, but it is to be understood that changes, variations and modifications can be resorted to which fall within the scope of the 25 claim hereunto appended.

In the drawings wherein like reference characters denote corresponding parts throughout the several views:

Figure 1 is a fragmentary view, in side elevation, of a washing machine of the rubber element type and showing the adaptation therewith of an attachment in accordance 35 with this invention.

Figure 2 is a fragmentary view, in plan, of 40 a washing machine and illustrating the adaptation of the attachment, in accordance with this invention with respect to the tub and rubber element.

Referring to the drawings in detail 1 45 denotes a tub, 2 the supporting legs therefor, 3 the rubber element which is mounted for oscillation upon a yoke-shaped hanger or bail 4 and 5 a handle member for the element 3. The hanger or bail 4 is mounted in pivots, 50 only one of which is shown and indicated at 6. The foregoing elements are of known construction and no claim is made thereto, but are illustrated and referred to for the purpose of showing the adaptation therewith of 55 a rubber element sustaining or holding attachment in accordance with this invention.

The rubber element sustaining or holding attachment co-acts with an arm of the hanger or bail 4 when the latter is swung vertically for the purpose of retaining the element 3 in the position shown in Figure 1 whereby the water dripping, discharging or draining from the element 3 can be directed into the tub 1. The attachment includes a latching member and a stop member therefor. The 60 latching member is referred to generally by the reference character 7 and the stop member generally by the reference character 8. The members 7 and 8 are arranged in an upstanding position with respect to the tub 1 and incline towards each other and with the member 8 extending into the member 7 to prevent an inward shift thereof with respect to the tub. The members 7 and 8 are arranged on the same side of the tub.

The member 7 comprises a lower part 9, an intermediate part 10, and an upper part 11. The lower part 9 is positioned against the outer face of one side of the tub 1 between the vertical center of said side and one end of the tub. The part 9 extends upwardly at an inclination and toward the other end of the tub and further extends across the vertical center of said side. The lower portion of the part 9 is fixedly secured by holdfast devices 12 to the tub 1, and is overlapped by a keeper 13, fixedly secured by holdfast devices 14 to the said side of the tub. The intermediate part 10 is inset with respect to the part 9 and is of curvilinear contour. The intermediate 80 part is disposed at an upward inclination and extends over the top edge 15 of that side of the tub to which the part 9 is attached. The upper part 11 of the member 7 is disposed longitudinally of the tub and at an angle with 85 respect to the part 10. The part 11 includes an outwardly directed, inwardly opening latching yoke 16 disposed over said top edge 15. The inner end of one arm of the yoke 16 merges into an outwardly directed curved 90 portion 17, and its other side, at its inner end merges into a longitudinally disposed, rearwardly extending portion 17', terminating in the inner end of the part 10, the latter providing means for directing the hanger or 95 bail 4 into the portion 16 to latch it in an elevated position. The member 7 is resilient. When the side arm of the bail or hanger 4 rides against the part 10 the upper part of the member 7 will be forced outwardly until 100 the said arm of the hanger or bail 4 clears the portions 10 and 17', at which time the upper 105 portion 17' will snap back into the position shown in Figure 1. The member 7 is resilient 110 and will return to its original position when the bail 4 is moved.

part of the member 17 will spring inwardly and the latching portion 16 will overlap the arm of the bail and thereby latch the same from movement, under such conditions holding the rubber element 3 in the position shown in Figure 1 and so the lower end of said element 3 will be spaced over the tub whereby when the rubber is turned the drippings therefrom, or the draining or discharging of the water therefrom will be directed directly into the tub. When it is desired to release the rubber element 3 the member 7 at its upper portion is swung outwardly so that the bail can clear the portion 16 and the rubber element 3 can be lowered. The stop member 8 extends into the yoke-shaped portion 16 and arrests inward movement of the upper part 11 of the member 7.

The stop member 8 extends above the tub 1, is formed from a flat bar having its lower portion fixedly secured to the tub, in proximity to the edge 15 thereof, by the holdfast devices 18. The member 8 inclines slightly forward from its lower to its upper end. The members 7 and 8 project a substantial distance above the top of the tub 1, but the member 8 is not arranged in the path of the hanger or bail 4. The upper and intermediate parts of the member 7 are arranged in the path of the hanger or bail 4 so that said member 11 can receive the bail and detachably latch it from movement to maintain the rubber element 3 stationary and in an upright position. The curved portion 17 facilitates for the shifting of the portion 11 outwardly to release the bail therefrom.

The attachment provides means for holding the rubber element stationary above the tub and in a position whereby the dripping of the water therefrom or rather drainage or discharge of the water therefrom will flow directly into the tub 1 and not upon the

ground or around the tub and therefore it is thought the many advantages of an attachment, in accordance with this invention for the purpose set forth can be readily understood, and although the preferred embodiment of the invention is as illustrated and described, yet it is to be understood that changes in the details of construction can be had which will fall within the scope of the invention as claimed.

What I claim is:—

An attachment for washing machines of that type including a tub and an oscillatory rubber element suspended by an upwardly shiftable, pivoted bail connected to the tub, comprising an upstanding, resilient latching member having its lower end anchored to one side of the tub, said member having an upwardly inclined part, and a curved part inset with respect to the inclined part and extending over the top edge of said side into the path of one side of the bail when the latter is swung upwardly, said member further formed with a part disposed longitudinally with respect to the top and at an angle to said inset part, said longitudinal part including an inwardly opening, outwardly disposed yoke arranged over said edge for the reception of said side of the bail to detachably secure the rubber element in a vertical position to provide for the drainage therefrom entering the tub, said longitudinal part further including portions extending from opposite sides of the yoke at the open end of the latter, one of said portions directed outwardly upon a curve and the other of said portions disposed at right angles to the yoke and merging into said inset part.

In testimony whereof, I affix my signature hereto.

WILLIAM G. HAEHL.
